UNITED STATES PATENT OFFICE

2,030,591

SEED MIXER AND AGITATOR

Albert Holmquist, Holmquist, S. Dak.

Application May 31, 1934, Serial No. 728,423

4 Claims. (Cl. 259—82)

My invention relates generally to apparatus for handling, mixing, and agitating granular material such as seeds, and an important object of my invention is to provide a device of this character which is simple and inexpensive and may be either power or hand operated.

It is also an important object of my invention to provide a device of the character indicated which is capable of handling containers of different sizes for containing the granular material.

It is also an important object of my invention to provide a device of the character indicated embodying means for holding the container in different positions while the same is being revolved to mix and agitate the granular material therein.

Other objects and advantages of my invention will be apparent from a reading of the following description in connection with the drawings, wherein for purposes of illustration I have shown a preferred embodiment of my invention.

In the drawings:—

Figure 1 is a side elevational view of the embodiment.

Figure 2 is a top plan view of Figure 1.

Figure 3 is an end elevational view taken from the left of Figure 1.

Figure 4 is a view similar to Figure 3 but showing the container mounted in a position at right angles to that in which it is shown mounted in Figure 3.

Figure 5 is a top plan view showing the container in its frame or cradle.

Figure 6 is an end elevational view of a portion of the container.

Figure 7 is a longitudinal vertical sectional view through Figure 6.

Figure 8 is a longitudinal vertical sectional view through the container.

Figure 9 is a transverse vertical sectional view through Figure 8.

Figure 10 is a perspective view of a portion of one of the connecting links of the side members of the cradle.

Figure 11 is a perspective view of a portion of one of the side members of the cradle.

Figure 12 is a transverse vertical sectional view showing the toothed wheel on the operating shaft and its pawl.

Figure 13 is a perspective view of one of the slide latches.

Referring in detail to the drawings, the numerals 5 and 6 refer respectively to end members of the supporting frame of the device each of which is composed of a straight inclined standard

7 and a bent inclined standard 8 joined at their lower ends by a bar 9; also joined at their upper ends by a bar 10 overlying which and connected to which is a bar 11 which extends quite a distance beyond one side where it is connected to the standard 7 by an angulated brace 12. Crossed braces 13, 14 connect the standards 7 and also the standards 8 to properly space the end members 5 and 6 as shown in Figure 1.

On the upper side of the bar 11 which is an angle iron there is mounted directly over the end members 5, 6, respectively, bearings 15, 16, respectively, journaling the operating shaft 17 which has the operating handle 18 outward of the end member 6 as shown in Figure 1. The opposite end of the operating shaft 17 has inwardly of the end member 5 a sprocket wheel 21 over which is trained a chain 22 which is trained over the larger sprocket wheel 23 which is fixed on the stub shaft 24 which is mounted in the bearing 25. This bearing 25 and the bearing 26 are mounted on the bars 11 and directly over and between the standards 7 and 8 of the end members 5, 6 respectively.

The sprocket 23 is located intermediate the ends of the stub-shaft 24 one end of which is journaled in the bearing 25 and the opposite end has fixed thereto the elongated plate 28 which is provided with the longitudinally spaced bolt holes 29. Axially aligned with the stub-shaft 24 is the stub-shaft 30 which has fixed to one end the elongated plate 31 provided with the bolt holes which are similar to the holes 29 in plate 28. Shaft 30 has its opposite end journaled in the bearing 26 outwardly of which it is provided with the toothed wheel 19 with which is engageable the pawl or shaft locking dog 20. It will be obvious that by rotating the handle 18 the sprocket chain connection will drive the stub-shaft 24 and the frame or cradle generally designated 33 which is mounted thereon and also on the elongated plate 31, if the dog 20 is disengaged.

The cradle 33 is composed of two side members 34, 35 each of which is elongated and U-shaped and provided in its legs with bolt holes 36 to receive bolts 37, 38, respectively which are adjustably placed in these holes and in the holes of the elongated plates 28, 31 to predetermine the width of the cradle for accommodating containers 39 of different sizes and shapes.

Fixedly mounted on the eight portions of the side members 34, 35 are the toothed wheels 40, 41 respectively, with which are engageable spring pressed sliding latches 42, 43, respectively each of which is slidably mounted in the brackets 44, 44' and 45 connected to the side members 46, 47, 55

respectively, of the longitudinal side members of the clamp structure which immediately engages the exterior of the container 39 to hold the same in the cradle in the position of angularity with respect to the cradle which is determined by the release of and the subsequent selective placement of the latches 42, 43 with the teeth of their respective toothed wheels 40, 41. By means of this arrangement the container may be positioned at right angles to the cradle as shown in Figure 4 or axially aligned with the cradle as shown in Figure 1 or in some selected intermediate position, according to the type of mixing or agitating to be done. Pivots 40' pass through the central portions of the side bars of the cradle and through the toothed wheels 40 and 41 respectively and enter pivot holes in the side members 46 and 47 so that said side members and the container can rotate on the pivots when the latches 42 and 43 are in releasing position.

The clamp structure of which the side members 46, 47 form a part includes the adjustable bands or straps 48, 49 at one end and 50, 51 at the opposite end for encircling the container 39 near the ends thereof. Nuts 52 on the ends of the bands which pass through the side members 46, 48 enable clamping the bands tightly around the container 39 in an obvious manner. A convenient lever 72 is pivotally mounted on each of the side members 46, 47 for operating the respective latches 42, 43 into and out of selective engagement with their respective toothed wheels 40, 41.

The container 39 is of the metallic drum type having the extruded annular shoulders 53, 54 strengthening the sides thereof and providing for ease in handling.

On the discharge end of the container 39 is an eccentrically located reduced neck 55 which has on its outer end a flange 56. A telescoping stopper 57 has the flange 58 for engaging the flange 56 while the cylindrical portion 59 is telescoped within the neck 55. A handle 60 having side portions 61 and 62, respectively, is fixed to the outer end of the stopper. Spring clips 63, 64 are hinged as indicated at 65, 66, respectively, to the end portions of the parts 61, 62 to be snapped around the flanges 58, 56 and engaged behind the flange 56 to hold the cover removably in place. The flange 56 on the neck 55 also provides means for connecting a sack or bag to the neck 55 by contracting the bag around the neck 55 behind the flange 56.

Within the neck 55 and extending in axial alignment to the opposite end of the container are flat agitator bars 67 which are attached to the neck as indicated at 58 and attached to the opposite end of the container by laterally directed portions as indicated at 59. The agitator bars 67 are circumferentially spaced with regard to the neck 55 and operate in an eccentric position during the rotation of the container on its axis to adequately mix and agitate the contents of the container. These agitator bars also act efficiently while the container is in the right angulated position shown in Figure 4 to mix and agitate the contents in the container while it is being revolved in the position shown in Figure 4.

Referring again to the latch mechanism which is common to both sides of the clamp which directly holds the container 39, it will be found shown in Figure 5 that the latch 42 has its wide portion slidably confined by the bracket 44 and

has its operative end portion confined by another bracket 44' which also overlies the toothed wheel 40. The reduced portion 68 of the latch has circumscribed thereon the spring 69 which works between the shoulder 70 and the bracket 45. A pin 71 projecting from the wide portion of the latch is engageable by the operating lever 72. The operating lever being pivoted as indicated at 72' withdraws the latch from its toothed wheel when the lower part of the lever 72 is swung toward the right. The levers 72 are connected by the rod 73 so that the levers can be operated in unison. Although I have shown and described herein a preferred embodiment of my invention, it is to be definitely understood that I do not desire to limit the application of the invention thereto, and any change or changes may be made in material and structure and arrangement of parts within the spirit of the invention and the scope of the subjoined claims.

What is claimed is:

1. An agitating and mixing device of the character described, said device comprising a support, a laterally expansible cradle revolvably mounted on said support, a container clamping frame pivotally connected to the opposite sides of said cradle, said frame being arranged for clamping a longitudinally disposed container, and adjustable means pivotally connecting the side of said clamping frame to a side of said cradle, said means comprising a pivot mounted on said side of the cradle, a toothed wheel concentric with said pivot and fixed against rotation relative to said side, and dog means mounted on said side of the clamping frame and normally engaging said toothed wheel to lock said frame from rotating relative to said cradle.

2. An agitating and mixing device of the character described, said device comprising a support, a laterally expansible cradle revolvably mounted on said support, a container clamping frame pivotally connected to the opposite sides of said cradle, said frame being arranged for clamping a longitudinally disposed container, said clamping frame including side members, container encircling members connected to said side members, and means for expanding and contracting said container encircling means.

3. In a device of the class described, a cradle including a pair of substantially U-shaped side bars and a pair of end bars, means for adjustably connecting the end bars to the limbs of the side bars, a trunnion extending outwardly from the central portion of each end bar, a supporting frame in which the trunnions are rotatably arranged, means for rotating one trunnion, a container clamping frame, said clamping frame including side members placed inwardly of the side bars, pivots connecting the central portions of said side bars with the side members of the frame, latch means for holding the clamping frame either parallel with the cradle or in different angular positions relative to the cradle, and means for adjusting the clamping frame to suit different sizes of containers.

4. In a device of the class described, a cradle, means for rotating the cradle, a clamping frame pivotally supported in the cradle, means for adjusting the width of the cradle, means for adjusting the frame relative to the cradle and means for adjusting the clamping frame to suit different sizes of containers.

ALBERT HOLMQUIST.
